BEDSPRING

William J. Duvall and Gerald W. Froemke, St. Louis, Mo., assignors to Smith & Davis Manufacturing Company, St. Louis, Mo., a corporation of Missouri

Application January 25, 1937, Serial No. 122,183

7 Claims. (Cl. 5—248)

This invention pertains to bedsprings and in particular to a double-bed spring, that is a spring for a double bed.

It has been a recognised difficulty in connection with double beds that when one of the occupants thereof is heavier than the other, the bedspring is depressed to a greater extent on the side of the heavy occupant than on the other side, and as a consequence, said other side tends to slope laterally toward the more depressed side. This causes discomfort to the lighter weight occupant on account of the sloping position of the bed.

One of the objects of this invention, therefore, is to provide a spring for a double bed so constructed and arranged that excessive compression of one side thereof will not effect the compression of the other side.

Another object of this invention is to provide such a structure made up in a single unitary spring mattress for a double bed.

Another object is to provide such a double-bed spring in which the region along the middle of the bed between the two occupants thereof is stiffened so as to counteract any tendency for excessive compression of one side to drag down the other side.

Further objects will appear from the following description taken in connection with the accompanying drawing in which

30 Figure 1 is a plan view of a double-bed spring embodying this invention with part broken away to show the intermediate structure. In this figure a transverse portion across the middle thereof has been broken out so as to shorten the drawing.

35 Figure 2 is a transverse section somewhat enlarged taken on line 2—2 of Figure 1.

The bedspring of this invention comprises an upper supporting frame 1, a lower supporting frame 2 and a series of bed supporting springs indicated generally at 3 which are suitably supported between the upper and lower frames 1 and 2. In order to support the springs 3 the lower frame is provided with a plurality of transverse supporting members 4 each of which supports a transverse row of springs 3, said springs being connected to the supporting member in any suitable manner. Longitudinal supporting wires or rods 5 connect the supporting members 4 with each other and with the ends of the lower frame 2. These wires or rods may also be connected to the springs 3. In the upper face of the bedspring the upper ends of the springs 3 are connected to each other by means of interlaced cross springs 6 in the usual manner.

55 In accordance with the present invention the

series of springs 3 is divided along the middle of the bed into two distinct side groups. These two groups are entirely separated from each other along the middle of the bed except for the connections already mentioned in the upper and lower faces of the bedspring, that is, in the planes of the frame 1 and the lower supports 4. Each of these groups is embraced by a separate group frame 7 constructed of heavy wire or other suitable material and located in a plane intermediate the upper and lower faces of the bedspring. The mid-portions of the springs 3 of each of these separate groups are connected to their respective group frames 7 by means of transverse connectors 8 and longitudinal connectors 9. These connectors may be in the form of simple wires suitably interlaced with or otherwise connected with the springs 3 at their midportions and connected at their ends to the frames 7. This provides independent supporting means for each group of springs so that their midportions are reinforced or supported to prevent lateral buckling thereof under pressure.

In addition to the group frames 7 an intermediate main frame 10 embraces both groups of springs and may, in fact, be arranged to surround all of the springs 3 as shown in Figure 1. The group frames 7 are connected to the intermediate main frame 10 by supporting connectors 11. The frame 10 thus provides an intermediate support for the midportions of all the bedsprings and more particularly a unitary support for the two group frames 7.

In order to stiffen the middle portion of the bed the two rows of springs extending down the middle of the bed are made stronger or stiffer than the rest of the springs 3 by constructing them of larger size wire or by any other suitable means. These stronger springs are indicated at 12. The end springs in each of these middle rows may or may not be stiffened or strengthened as described. These extra strong springs along the inner edge serve to stiffen or strengthen said inner edge of each side group of springs so that such edge is enabled to resist being dragged downwardly by excessive compression of the other half of the bed.

It will be noted, therefore, that this invention provides a unitary structure for a double-bed spring in which the two side halves are freed from each other for independent operation. It will be noted that the two side groups are entirely separate from each other except that they are connected to a common supporting structure at their bottom, that is at the supports 4, and

that they are interconnected at their upper ends in the plane of the upper frame 1 by the top springs 6. These top springs are relatively light and serve simply to prevent wobbling of the upper ends of the springs and will have comparatively little effect in transmitting the compression from one side of the bed to the other. Accordingly, when a heavy person occupies one side of the bed, the side group of springs on that side 10 may yield to properly support his weight and in so doing is reinforced and supported by connections to the upper and lower frame and also by connections of the midportions of the springs to the intermediate main frame 10. Such yielding 15 will have substantially no effect upon the other side groups, since the only connection thereto is through the top springs 6 which are too light to cause any substantial compression of the springs 12. The independent action of the two side 20 groups is further enhanced by the fact that the two middle rows of springs 12 are stiffer or stronger than the other springs. This provides a stiffened inner edge for each side group. This stiffening has a dual effect. It not only enables the side 25 group occupied by the heavy person to support his weight without excessive sagging along the middle of the bed and thereby reduces the actual sag at that point, but, since the inner edge of the other side group is also stiffened in like manner, 30 it is better able to resist the tendency of the occupied side group to drag it down. Furthermore, since there are no connections between the side groups at any intermediate point between the upper and lower faces of the bedspring, there can 35 be no transmission of pull from one side to the other except through the springs 6 which, as already pointed out, are too weak to have any substantial effect.

Accordingly, this structure provides a bed-spring for a double bed which may be occupied 40 by persons of greatly unequal weight and is adapted to support the weight of each person independently of that of the other so that the bed surface is maintained substantially level for each lateral half thereof and greater comfort is thereby afforded to both occupants of the bed. Furthermore, this effect is obtained in a unitary structure and without any necessity for adjustment or manipulation.

50 The connection of the group frames 7 to the intermediate main frame 10 by the connectors 11 provides not only lateral support for the side groups of springs but a certain amount of vertical support. The connectors 11 form a sort of hinge connection between the frames 7 and 10 permitting depression of the former to a limited extent but resisting an excessive amount of compression, and thereby cooperates with the inner row of springs 12 to maintain each half of the 55 bed level by supporting the margins thereof.

However, while great advantages are obtained from this device as a unitary structure, it will be understood that individual features or sub-combinations thereof may be useful by themselves without reference to the complete combination, and the employment of such individual features or subcombinations is contemplated by this invention and within the scope of the appended claims.

70 It is further obvious that various changes may be made in the details of construction within the scope of the appended claims without departing from the spirit of this invention, and it is understood, therefore, that the invention is not limited to the specific details shown or described.

Having thus described the invention, what is claimed is:

1. A double-bed spring, comprising, upper and lower supporting frames, bed-supporting springs supported between said frames, certain of said springs being grouped to provide two distinct side groups, the springs of the two middle rows along the bed being stiffer than the other springs of said groups, and means laterally supporting the mid-portions of the springs of each of said side 10 groups, said groups including said lateral supporting means being unconnected to each other except through their lower supports and extensible mattress-supporting elements interconnecting the upper ends of said springs, so that each 15 group is unaffected by deflection of the other.

2. A double-bed spring, comprising, upper and lower supporting frames, bed-supporting springs supported between said frames, certain of said springs being grouped to provide two distinct side 20 groups, the springs of the two middle rows along the bed being stiffer than the other springs of said groups, means laterally supporting the mid-portions of the springs of each of said side groups, and an intermediate main frame to which said 25 supporting means are connected, said groups including said lateral supporting means being unconnected to each other except through their lower supports and extensible mattress-supporting elements interconnecting the upper ends of 30 said springs, so that each group is unaffected by deflection of the other.

3. A double-bed spring, comprising, upper and lower supporting frames, bed-supporting springs supported between said frames, certain of said 35 springs being grouped to provide two distinct side groups, the springs of the two middle rows along the bed being stiffer than the other springs of said groups, means laterally supporting the mid-portions of the springs of each of said side 40 groups, an intermediate main frame, a pair of group frames each embracing one of said side groups of springs, and means connecting said supporting means to said group frames, and said group frames to said intermediate main frames, 45 said groups including said lateral supporting means being unconnected to each other except through their lower supports and extensible mattress-supporting elements interconnecting the upper ends of said springs, so that each group is 50 unaffected by deflection of the other.

4. A double-bed spring, comprising, upper and lower supporting frames, bed-supporting springs supported between said frames, certain of said 55 springs being grouped to provide two distinct side groups, the springs of the two middle rows along the bed being stiffer than the other springs of said groups, means laterally supporting the mid-portions of the springs of each of said side groups, an intermediate main frame, and hinging 60 connections between said supporting means and said main frame, said groups including said lateral supporting means being unconnected to each other except through their lower supports and extensible mattress-supporting elements in- 65 terconnecting the upper ends of said springs, so that each group is unaffected by deflection of the other.

5. A double-bed spring, comprising, upper and lower supporting frames, bed-supporting springs 70 supported between said frames, certain of said springs being grouped to provide two distinct side groups, means laterally supporting the mid-portions of the springs of each of said side groups, said groups including said lateral supporting 75

means being unconnected to each other except for their lower supports and extensible mattress-supporting elements interconnecting the upper ends of said springs, and an intermediate main frame to which said supporting means are connected.

6. A double-bed spring, comprising, upper and lower supporting frames, bed-supporting springs supported between said frames, certain of said springs being grouped to provide two distinct side groups, a pair of independent group frames each embracing one of said side groups, connections from each frame to the intermediate portions of the springs in its group, the inner row of springs of each of said groups being stiffer than the other springs thereof, an intermediate main frame, and hinging connections between said group frames and said main frame.

7. A double-bed spring, comprising, upper and

lower supporting frames, bed-supporting springs supported between said frames, certain of said springs being grouped to provide two distinct side groups, a pair of independent group frames each embracing one of said side groups, connections from each frame to the intermediate portions of the springs in its group, the inner row of springs of each of said groups being stiffer than the other springs thereof, an intermediate main frame, and hinging connections between 10 said group frames and said main frame, said groups including said group frames being unconnected to each other except through their lower supports and extensible mattress-supporting elements interconnecting the upper ends of said 15 springs so that each group is unaffected by deflection of the other.
